(57) **CLAIM**

The ornamental design for a light source module, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view, from the top, of a first preferred embodiment of a light source module in accordance with the new design;

FIG. 2 is a perspective view thereof, from the bottom;

FIG. 3 is a front view thereof;

FIG. 4 is a right side view thereof;

FIG. 5 is a left side view thereof;

FIG. 6 is a rear view thereof;

FIG. 7 is a top view thereof; and

FIG. 8 is a bottom view thereof.

FIG. 9 is a perspective view, from the top, of a second preferred embodiment of a light source module in accordance with the new design;

FIG. 10 is a perspective view thereof, from the bottom;

FIG. 11 is a front view thereof;

FIG. 12 is a right side view thereof;

FIG. 13 is a left side view thereof;

FIG. 14 is a rear view thereof;

FIG. 15 is a top view thereof; and,

FIG. 16 is a bottom view thereof.

The broken lines in the drawings illustrate environmental structure and form no part of the claimed design.

1 Claim, 8 Drawing Sheets
